UNITED STATES PATENT OFFICE.

WILLIAM H. SHICK, OF READING, PENNSYLVANIA, ASSIGNOR TO THE READING STOVE WORKS, ORR, PAINTER & CO., OF SAME PLACE.

DESIGN FOR AN AIR-CONDUIT FIRE-POT.

SPECIFICATION forming part of Design No. 31,445, dated August 22, 1899.

Application filed June 17, 1899. Serial No. 720,987. Term of patent 7 years.

To all whom it may concern:

Be it known that I, WILLIAM H. SHICK, a citizen of the United States of America, and a resident of Reading, in the county of Berks and State of Pennsylvania, have invented a certain new and original Design for an Air-Conduit Fire-Pot, of which the following is a specification.

My invention relates to a form of fire-pot embodying, in connection with the fire-walls of a heater or furnace, an air-passage encircling the upper portion of the fire-chamber and having outlets into the latter, as indicated in the drawing, which is a perspective view of my fire-pot.

The essential features of my design comprise a cylindrical pot or chamber *a*, having an annular seat *b* to rest upon a suitable

heater-base, an enlarged top *c*, having an annular air passage or conduit formed therein, ²⁰ with a peripheral air-inlet extension *d*, designed to communicate through the registered front of the heater with the outside air, a circular series of interior air-exits *e* into the top of the chamber, and an annular sand joint or ²⁵ recess *f*, designed as a seat for a combustion-chamber to be supported thereon.

What I claim is—

The design for an air-conduit fire-pot substantially as shown and described. ³⁰

Signed by me, at Reading, Pennsylvania, this 8th day of June, 1899.

WILLIAM H. SHICK.
